[57] CLAIM

The ornamental design for a blower, substantially as shown and described.

DESCRIPTION

FIG. 1 is a side elevational view of a blower showing my new design;

FIG. 2 is a view in elevation as seen from the opposite side of FIG. 1;

FIG. 3 is a view in elevation as seen from the left of FIG. 2;

FIG. 4 is a top view thereof as seen from above in FIG. 2;

FIG. 5 is a view in elevation as seen from the right in FIG. 2;

FIG. 6 is a side elevational view of a second embodiment of the blower of my new design;

FIG. 7 is a view in elevation as seen from the opposite side of FIG. 6;

FIG. 8 is a view in elevation as seen from the left of FIG. 7;

FIG. 9 is a top view thereof as seen from above in FIG. 7;

FIG. 10 is a view in elevation as seen from the right in FIG. 7;

FIG. 11 is a side elevational view of a third embodiment of the blower of my new design;

FIG. 12 is a view in elevation as seen from the opposite side of FIG. 11;

FIG. 13 is a view in elevation as seen from the left of FIG. 11;

FIG. 14 is a top view as seen from above in FIG. 11;

FIG. 15 is a view in elevation as seen from the left in FIG. 12;

FIG. 16 is a side elevational view of a fourth embodiment of the blower of my new design;

FIG. 17 is a view in elevation as seen from the opposite side in FIG. 16;

FIG. 18 is a view in elevation as seen from the left of FIG. 17;

FIG. 19 is a top view thereof as seen from above in FIG. 17;

FIG. 20 is a view in elevation as seen from the left in FIG. 16.
